UNITED STATES PATENT OFFICE.

HENRY D. BULTMAN, OF NEW YORK, N. Y., ASSIGNOR TO CONSOLIDATED DENTAL MANUFACTURING COMPANY, OF NEW YORK, N. Y., A CORPORATION OF NEW YORK.

WALL-BRACKET.

1,176,272.

Specification of Letters Patent. Patented Mar. 21, 1916.

Application filed May 21, 1914. Serial No. 840,022.

To all whom it may concern:

Be it known that I, HENRY D. BULTMAN, a citizen of the United States, and a resident of the borough of Brooklyn, in the 5 city and State of New York, have invented a new and useful Improvement in Wall-Brackets, of which the following is a specification.

The object of this invention is to provide 10 means whereby a wall bracket may be adjusted after its socket pieces have been secured to the wall so as to bring the bracket into a true vertical position.

A further object is to provide certain 15 other features in a pivoted adjustable wall bracket whereby the same may be adjusted very easily and accurately to the desired position.

A practical embodiment of my invention 20 is represented in the accompanying drawings, in which—

Figure 1 represents the bracket in top plan, the sliding parallel bars being shown in full lines in one position and in dotted 25 lines in another position, Fig. 2 represents a view in side elevation partly in section of the bracket, the parts being shown in one position in full lines and in two other positions in dotted lines, Fig. 3 is a front view 30 of the upper fixed wall socket, Fig. 4 is a transverse section taken in the plane of the line A—A of Fig. 3, Fig. 5 is a vertical section taken in the plane of the line B—B of Fig. 3, Fig. 6 is a detail view showing the 35 bearings for one of the parallel bars of the bracket, and Fig. 7 is a detail section taken in the plane of the line C—C of Fig. 1.

The spider to which the table is secured is denoted by 1, which spider is provided 40 with a pivot 2 rotatable in a cross piece 3 which spaces the outer ends of two horizontally arranged parallel bars 4, 5, slidable in the head 6 of the outer member 7 of the bracket arm. This outer member 7 is pivoted 45 at 8 to the outer end of the intermediate member 9 of the bracket arm, the inner end of which member is pivoted at 10 to the inner member 11 of the said arm. The inner member 11 has top and bottom convex- 50 sided hinge pintles 12, which are inserted in straight-sided bores 13 of bearings 14 located in recesses 15 of top and bottom

socket pieces 16 fixed to the wall or other vertical support by fastening means such, for instance, as screws 17.

55

Each bearing 14 may be adjusted laterally outwardly and inwardly in its recess 15 so as to bring the bracket arm into a true vertical position so that the bracket arm will stay in any of its adjusted positions when swung to such positions on the hinge pintles 12. Each of these bearings 14 has a sliding interlocked engagement with and is laterally adjusted by a screw 18 rotatably mounted in the socket piece. This 60 screw is held against removal, as, for instance, by a pin 19 entering a circumferential recess 20 in said screw.

65

A traveling nut 21 on the screw is provided with flattened surfaces engaging the 70 upper and lower walls of a slot 22 in the bearing, said traveling nut having flanges 23 arranged to engage the bearing to move it laterally in either direction according to the direction which the screw 18 is turned. 75 Each of these bearings is adjusted outwardly and inwardly by an adjusting screw 24 screw threaded in the socket piece 16. The bearing 14 has an interlocked sliding engagement with the screw 24 through a 80 sliding block 25 carried by the inner end of the screw whereby the bearing may be moved laterally on the head and yet will be moved outwardly or inwardly along the recess 15 by the turning of the screw in one 85 or the other direction. The outer end of the screw may have a kerf 26 and both ends of the screw 18 may have kerfs 27 for insertion of a tool for turning them. By these 90 adjustments, the bracket arm may be accurately adjusted into the desired position to swing properly irrespective of the wall or other support to which it is attached.

The intermediate member 9 of the bracket arm may be adjusted vertically to different 95 positions and held in such adjustments by providing the inner member 11 with a ratchet 28 and the intermediate member 9 with a pawl 29 arranged to engage said ratchet. This pawl is provided with a stem 100 30 slidably mounted in the intermediate member 9. A spring 31 serves to hold the pawl in engagement with the ratchet 28. The pawl may be drawn outwardly out of

engagement with the ratchet by means of a handle 32 slideable along the under side of the intermediate member 9 of the arm and secured at 33 to the outer end of the stem 30 of the pawl. This handle has a finger piece 34 for facilitating its operation.

The outer member 7 of the bracket arm is maintained in its vertical position irrespective of the adjustment of the intermediate member 9 by providing a connecting rod comprising inner, outer and intermediate sections 35, 36, 37. The inner and outer ends of this connecting rod are pivoted to the inner and outer members of the bracket arm 10 at equal distances from the pivotal connections 10 and 8. The intermediate section 37 of this connecting rod is rotatably engaged at 38 with the outer section 36 and has a screw threaded engagement, as shown at 39, 15 with the inner section 35 so that by turning the intermediate section 37 the outer member 7 of the bracket arm may be accurately adjusted to its vertical position.

To insure the easy sliding of the parallel bars 4, 5, in the head, the bore for each bar is preferably made larger than the bar and end bearings 40 are provided which snugly fit the bar and are held in position by screw caps 41. These bearings may be readily replaced when worn.

While I have shown and described my invention in connection with a dental wall bracket, it is to be understood that I do not wish to limit myself to this particular type 25 of wall bracket but contemplate the use of my improvement in wall brackets of all types wherever applicable.

What I claim is:

1. A wall bracket comprising a laterally 40 swinging arm having top and bottom hinge pintles, upper and lower fixed wall socket pieces, bearings therein for said hinge pintles and means for moving the upper bearing laterally to adjust the top of the arm.

2. A wall bracket comprising a laterally 45 swinging arm having top and bottom hinge pintles, upper and lower fixed wall socket pieces, bearings therein for said hinge pintles and means for moving the upper bearing outwardly and inwardly to adjust the top of the arm.

3. A wall bracket comprising a laterally 55 swinging arm having top and bottom hinge pintles, upper and lower fixed wall socket pieces, bearings therein for said hinge pintles and means for moving the upper bearing laterally and outwardly and inwardly to adjust the top of the arm.

4. A wall bracket comprising a laterally 60 swinging arm having top and bottom hinge pintles, upper and lower fixed wall socket pieces, bearings therein for said hinge pintles and means for moving the lower bearing laterally to adjust the bottom of the arm.

5. A wall bracket comprising a laterally

swinging arm having top and bottom hinge pintles, upper and lower fixed wall socket pieces, bearings therein for said hinge pintles and means for moving the lower bearing outwardly and inwardly to adjust the 70 bottom of the arm.

6. A wall bracket comprising a laterally 75 swinging arm having top and bottom hinge pintles, upper and lower fixed wall socket pieces, bearings therein for said hinge pintles and means for moving the lower bearing laterally and outwardly and inwardly to adjust the bottom of the arm.

7. A wall bracket comprising a laterally 80 swinging arm having top and bottom hinge pintles, upper and lower fixed wall socket pieces, bearings therein for said hinge pintles and means for moving the upper and lower bearings laterally to adjust the top 85 and bottom of the arm.

8. A wall bracket comprising a laterally 90 swinging arm having top and bottom hinge pintles, upper and lower fixed wall socket pieces, bearings therein for said hinge pintles and means for moving the upper and lower bearings outwardly and inwardly to adjust the top and bottom of the arm.

9. A wall bracket comprising a laterally 95 swinging arm having top and bottom hinge pintles, upper and lower fixed wall socket pieces, bearings therein for said hinge pintles and means for moving the upper and lower bearings laterally and outwardly and inwardly to adjust the top and bottom of the arm.

10. A wall bracket including a fixed wall 100 socket piece having a recess therein, a bearing in said recess and two screws for adjusting the bearing laterally and outwardly and inwardly, the bearing having a sliding interlocked engagement with both screws.

11. A wall bracket including a laterally 105 swinging bracket arm having a convex-sided hinge pintle, a fixed wall socket piece and an adjustable bearing therein having a straight-sided bore for receiving said pintle.

12. A wall bracket including a vertically 110 adjustable arm comprising an inner member, an intermediate member hinged thereto and an outer member hinged to the intermediate member, and an adjustable rod parallel to the intermediate member and hinged to the inner and outer members.

13. A wall bracket including a vertically 115 adjustable arm comprising inner, outer and intermediate members, an adjustable rod parallel to the intermediate member and hinged to the inner and outer members, said rod comprising inner and outer sections, and an intermediate section having a rotary connection with one of said sections and a screw threaded engagement with the other of said sections.

14. A wall bracket including a head, two 120 parallel bars sliding therein, the bore for 125

each bar being larger than the bar, and end bearings for the bars.

15. A wall bracket including a head, a bar sliding therein, the bore for the bar being larger than the bar, and end bearings for the bar.

In testimony, that I claim the foregoing

as my invention, I have signed my name in presence of two witnesses, this first day of May 1914.

HENRY D. BULTMAN.
